DESIGN FOR A PIPE COUPLING UNIT OR SIMILAR ARTICLE

Ivan Ročić, New York, N. Y.

Application August 14, 1943, Serial No. 110,916

Term of patent 14 years

(Cl. D91—3)

To all whom it may concern:

Be it known that I, Ivan Ročić, a citizen of Croatia, Jugoslavia, and a resident of the city of New York, county of New York, and State of New York, have invented a new, original, and ornamental Design for a Pipe Coupling Unit or Similar Article, of which the following is a specification, reference being had to the accompanying drawing, forming part thereof.

Figure 1 is a top plan view of a pipe coupling unit or similar article showing my new design;

Figure 2 is a transverse sectional view thereof

on the line 2—2 of Figure 1, other side is substantially the same;

Figure 3 is a longitudinal sectional view on the line 3—3 of Figure 1; and

Figure 4 is a transverse sectional view thereof on the line 4—4 of Figure 1.

The fragmentary pipe ends are shown for illustrative purpose only.

I claim:

The ornamental design for a pipe coupling unit or similar article, as shown and described.

IVAN ROČIĆ.
